UNITED STATES PATENT OFFICE.

DAVID H. SIMPSON, OF NEW YORK, N. Y.

MACHINE FOR STRIPPING AND CUTTING TOBACCO LEAVES.

Application filed December 22, 1923. Serial No. 682,151.

The invention relates to improvements in tobacco leaf stripping and cutting machines which strip and cut the leaves of tobacco to prepare the same for use in the manufacture of cigars, smoking tobaccos, and the like.

The principal object of the invention is the provision of a device of this character which not only cuts the leaf of the tobacco from its stem, but also crushes and cuts the stem into strips so that it may also be utilized in the manufacture of cigars and smoking tobaccos.

A further object of the invention is to provide means in such a device whereby the stem of the tobacco leaf is crimped at the same time it is being cut into strips.

A further object of the invention is to provide means for rolling the leaf on a drum after it has been cut from its stem.

Further objects of the invention will appear more fully hereinafter, and I attain these objects by the mechanism illustrated in the accompanying drawings in which:

Figure 1 is a side elevation of a machine constructed according to my invention.

Figure 2 is a plan view of the same.

Figure 3 is a sectional view on the line 3—3, Figure 2 looking in the direction of the arrows.

Figure 4 is a plan view of the machine taken on the line 4—4 Figure 3.

Figure 5 is a partial sectional view taken on the line 5—5 of Figure 2 looking in the direction of the arrows.

Figure 6 is an end view taken on the line 6—6 of Figure 3 looking in the direction of the arrows.

Figure 7 is a sectional view on the line 7—7 Figure 3 looking in the direction of the arrows.

Figure 8 is a detail perspective view of a portion of the table or shelf along which the tobacco leaves are fed through the machine.

Figure 9 is a detail view of a portion of the cover for drum.

Like numerals refer to corresponding parts throughout the several views.

Referring to the several parts by their designating numerals, 1 indicates a table or shelf upon which the tobacco leaves to be stripped and cut, are placed for feeding into the machine. The table or platform is secured to any suitable support, as for instance to the housing or casing 9 as at 60.

Secured to the table or shelf in any suitable manner, as at 61, is a casing 2 which is adapted to enclose a drum 3. The casing is open as at 21 and its end 62 is slotted as 22 (see Fig. 9) so as to enable the end 62 to project above the table or shelf 1, said slot being adapted to receive the tongue 26 of said table as will be explained more fully hereinafter. The casing 2 is also provided with spring maintained rollers 23 which project towards and are in alignment with the drum 3.

The drum 3 is mounted on a shaft 4 which is rotatably secured to said casing in any suitable manner. Also secured to the shaft 4 is the gear 5 which is adapted to mesh with the gear 6.

The gear 6 is secured to a shaft 7 rotatably mounted in a support 8 secured to the casing 9 at 63, in any suitable manner.

Mounted on the shaft 7 is the circular cutter 10 having the spaced cutting blades 11 and 12. The cutting blades 11 and 12 are adapted to cooperate with the cutting blades 13 and 14 secured to the drum 3.

Also mounted on the support 8 are the rotatable shafts 15 and 16. Secured to shaft 15 is the guide roller 17 and the gear 19. Secured to the shaft 16 is the gear 20 adapted to mesh with gears 19 and 6.

The table or shelf 1 is provided with slots 24 and 25 therein, through which the blades 13 and 14 project and the cut-off ends 28 which are received in the open end of the casing 2. The tongue or extension 26 of said table or shelf, formed by the slots 24 and 25 and the cut-off ends 28, extends between and beyond the cutting blades and through the slot 22 in the casing 2 to a substantially widened portion 26^a. Secured to the widened portion 26^a is the guide way 27 having the covered portion 27^a and the side portions 29.

The guide roller 17 is adapted to operate between the side portions 29 of said guide way.

The above description relates to the mechanism employed, in accordance with my invention, for the purpose of stripping the tobacco leaf from the stem. I will now describe the mechanism employed for crushing, shredding and crimping the stem after it has been parted from the leaf.

Mounted in the housing 9 are the rotatable shafts 30, 31, 32, 33 and 34. Secured to the shafts 30 and 31 inside of said casing or housing, are the crushing rollers 35 and 36

so placed with relation to each other that they contact with each other as they revolve at 64. These rollers may be of steel or any other suitable material. Secured to the 5 shafts 30 and 31 on the outside of said casing or housing 9, are the gears 37 and 38.

Secured to the shafts 32 and 33 on the inside of the casing or housing 9, are the rollers 39 and 40 upon which are mounted 10 the spaced cutting elements 41 and 42 having knife edges. The knife edges on cutting element 41 on roller 39 are adapted to have a scissor-like cutting action with respect to the knife edges on cutting element 42 on roller 15 40. The cutting elements 41 and 42 are formed with the notches 46 which are arranged at spaced intervals in the elements.

The shafts 32 and 33 have secured thereto on the outside of the casing or housing 9, 20 the gears 43 and 44.

A shaft 34 is mounted in the casing or housing 9 and has secured thereto the gear 45 which is adapted to mesh with gears 37 and 43. The gears 37 and 43 are also so arranged 25 to mesh with the gears 38 and 44.

Rotatably mounted on shafts 47 and 48 in said casing 9, are the scraper blades 49 and 50. These blades are yieldingly maintained in contact with the surfaces of crushing rollers 35 and 36 by means of springs 51 and 52 on said shafts.

Mounted in the casing 9 in suitable manner, are the combs or pickers 53 which are so arranged that the points of the combs or pickers fit into the spaces between the cutting elements 41 and 42.

Secured to the gear 38 is one end of a crank lever 54 which is arranged to have its other end maintained in a guide support 55.

40 Intermediate its end the crank lever is provided with the rack portion 56. The rack portion 56 is adapted to cooperate with pinion 57 loosely secured to the shaft 4 of the drum 3. A ratchet wheel 58 is fixedly secured to the shaft 4 outside of the pinion 57, and a pawl 59 is attached to the pinion to engage with said ratchet wheel. The shaft 31 of the gear 38 is attached in any suitable manner with a source of power.

50 The operation of the structure as described is as follows:—

When power is applied to the shaft 31, motion is imparted to the gears 37, 38, 43 and 44 which in turn operate the rollers 35, 36, 55 41 and 42 in the casing 9, causing them to revolve in the directions indicated by the arrows in Figure 1. At the same time motion is imparted to the crank lever 54, thereby transmitting motion to the pinion 57 loosely secured to the shaft 4 of the drum 3. When the crank and rack are moved one way, the pinion turns loosely on the shaft; and when the crank and rack move the opposite way, the pinion turns the shaft by means of its 60 pawl and the ratchet wheel fast on the shaft 65

4, thereby causing an intermittent motion of the drum. This can be clearly understood from the drawings. When the shaft 4 is rotated as above explained, the drum secured to the shaft is rotated and the gear 5 which is in mesh with gear 6, imparts motion thereto which in turn moves gears 20 and 19, thereby causing the rotation of the circular cutting knives and the roller 17.

Tobacco leaves are fed to the rotating cutting knives 11 and 12 which cooperate with knives 13 and 14 so that the stem of the leaves passes between the said knives and the leaf is thereby cut away from the said stem. The leaf portions pass over the ends 28 of the table or shelf 1, and are guided onto the drum 3 by the open end of the casing 2.

After the leaf portion of the leaf is transferred to the drum, it is held in close contact therewith by means of the spring maintained rollers 23.

The stem portion of the leaf passes along the tongue or extension 26 of the table or shelf and under the covered portion of the guide way 27, where its progress is guided and helped along by the roller 17 operating in said guide way.

The stem then passes between the crushing rollers 35 and 36. The crushing rollers flatten out the stem and also progress the flattened stem to the stem cutting elements mounted on rollers 39 and 40. The scrapers 49 and 50 help to keep the rollers clean and also serve as guides for the crushed and flattened stem to the cutting elements. The flattened stem then passes between the spaced cutting elements on rollers 39 and 40, and is cut into strips by reason of the knife edges of said elements and, by reason of the spaced notches 46 in said knives, the strips are crimped. The stripped stem then passes from the cutting elements and said strips are picked therefrom and guided to the receiving table by the pickers or combs 53.

Having now described a construction embodying my invention, and without thereby desiring to be understood as unduly limiting myself, what I claim as new and useful, of my own invention and desire to secure by Letters Patent of the United States is:—

1. In a machine for stripping and cutting tobacco leaves the combination of a cutting mechanism to sever the leaf from its stem, means for cutting the stem into strips, means for advancing the stem from the leaf severing mechanism to the stem cutting mechanism, and means for transmitting power to said leaf severing and stem cutting means.

2. In a machine for stripping and cutting tobacco leaves the combination of a cutting mechanism to sever the leaf from its stem, means for cutting the stem into strips, means for advancing the stem from the leaf severing mechanism to the stem cutting mecha-

nism, means for transmitting power to said stem cutting means and means secured to said stem cutting power transmitting means to operate said leaf severing means.

5. 3. In a machine for stripping and cutting tobacco leaves the combination of a cutting mechanism to sever the leaf from its stem, means for cutting the stem into strips, means for advancing the stem from the leaf severing mechanism to the stem cutting mechanism, means for transmitting power to said stem cutting means and means secured to said stem cutting power transmitting means to intermittently operate said leaf severing means.

10. 4. In a machine for stripping and cutting tobacco leaves the combination of a cutting mechanism to sever the leaf from its stem, means for crushing the stem after the leaf has been severed therefrom, means for cutting the stem into strips, means for advancing the stem from the leaf severing mechanism to the stem crushing and cutting means, means for transmitting power to said stem crushing and cutting means and means secured to said power transmitting means to intermittently operate said leaf severing means.

15. 5. In a machine for stripping and cutting tobacco leaves the combination of a cutting mechanism to sever the leaf from its stem, means for cutting the stem into strips, means associated with said stem cutting means for crimping the strips, means for advancing the stem from the leaf severing mechanism to the stem cutting mechanism, and means for transmitting power to said leaf severing and stem cutting means.

20. 6. In a machine for stripping and cutting tobacco leaves the combination of a cutting mechanism adapted to sever the leaf from its stem, a drum upon which the severed leaf is wound, means for cutting the stem into strips after the leaf has been severed therefrom, means for feeding the stem to said stem cutting means and means for transmitting power to the leaf severing and stem cutting means.

25. 7. In a machine for stripping and cutting tobacco leaves the combination of a cutting mechanism adapted to sever the leaf from its stem, a drum upon which the severed leaf is wound, means for crushing the stem after the leaf has been severed therefrom, means for cutting the stem into strips after it has been crushed, means cooperating with said crushing means for feeding the crushed stem to said stem cutting means and means for transmitting power to the leaf severing, stem crushing and cutting means.

30. 8. In a machine for stripping and cutting tobacco leaves the combination of a cutting mechanism to sever the leaf from its stem, a drum upon which the severed leaf is wound, means for crushing the stem after the leaf

has been severed therefrom, means for cutting the stem into strips after it has been crushed, means for feeding said stem to said crushing and cutting means from said leaf severing mechanism, and power transmitting means for simultaneously actuating said leaf severing, stem crushing, stem cutting means and said drum.

35. 9. In a machine for stripping and cutting tobacco leaves the combination of a cutting mechanism to sever the leaf from its stem, a drum upon which the severed leaf is wound, means for crushing the stem after the leaf has been severed therefrom, means for stripping and crimping the stem after it has been crushed, means for feeding said stem to said crushing and cutting means from said leaf severing mechanism, and means for transmitting power simultaneously to the said severing, crushing, and cutting means and to said drum.

40. 10. In a machine for stripping and cutting tobacco leaves the combination of a cutting mechanism to sever the leaf from its stem, a drum upon which the severed leaf is wound, means for guiding said leaf on said drum, means for crushing said stem after the leaf has been severed therefrom, means for cutting the stem into strips and crimping the same, means for feeding the stem from the leaf cutting mechanism to the crushing, cutting and crimping means, and means for transmitting power to said severing, crushing, and cutting means and said drum.

45. 11. In a stripping and cutting machine for tobacco leaves the combination of rotary cutting blades adapted to sever the leaf from the stem, a drum upon which the severed leaf is wound, crushing rollers arranged so as to crush the stem after the leaf has been severed therefrom, rotary cutting knives for cutting the stem into strips, and driving means to simultaneously actuate said rotary cutting blades, crushing rollers, rotary cutting knives and said drum.

50. 12. In a stripping and cutting machine for tobacco leaves the combination of rotary cutting blades adapted to sever the leaf from the stem, a drum upon which the severed leaf is wound, cutting blades on said drum adapted to cooperate with said rotary cutting blades, driving mechanism for said drum, means secured to said drum for driving said rotary cutting blades, crushing rollers arranged so as to crush the stem after the leaf has been severed therefrom, means for cutting the stem into strips and crimping the said strips after the stem has been crushed, means for feeding the stem from said leaf severing blades to said crushing rollers and

55. cutting means, driving means for actuating said stem crushing rollers and rotary cutting knives, and means secured to said driving means for actuating the driving mechanism for said drum.

13. In a stripping and cutting machine for tobacco leaves the combination of rotary cutting blades adapted to sever the leaf from the stem, a drum upon which the severed leaf is wound, means for guiding said leaf on said drum, crushing rollers to crush said stem after the leaf has been severed therefrom, means for guiding said stem to said crushing rollers, rotary cutting knives 10 for cutting the stem into strips, and driving means to simultaneously actuate said rotary cutting blades, crushing rollers, rotary cutting knives and said drum.
14. In a stripping and cutting machine 15 for tobacco leaves the combination of rotary cutting blades adapted to sever the leaf from the stem, a drum upon which the severed leaf is wound, means for guiding said leaf on said drum, crushing rollers to crush 20 said stem after the leaf has been severed therefrom, means for guiding said stem to said crushing rollers, scraping means yieldingly engaging said rollers, rotary cutting knives for cutting the stem into strips after 25 it has been crushed, means for guiding the crushed stem to said rotary cutting knives, driving means for actuating said stem crushing rollers and rotary cutting knives, and means secured to said driving means 30 for actuating the driving mechanism for said drum.
15. In a stripping and cutting machine for tobacco leaves the combination of rotary cutting knives adapted to sever the leaf from its stem, a drum upon which the severed leaf 35 is wound, a cover for said drum, means yieldingly maintained in said cover to maintain said severed leaf on said drum, crushing rollers arranged so as to crush the stem 40 after the leaf has been severed therefrom, rotary cutting knives for cutting the stem into strips, means associated with said stem stripping knives for crimping the strips, means for advancing the stem from the leaf 45 cutting knives to the stem crushing rollers, and driving means to simultaneously actuate said leaf cutting knives, drum, crushing rollers and stem cutting knives.
16. In a stripping and cutting machine 50 for tobacco leaves the combination of rotary cutting knives adapted to sever the leaf from its stem, a drum upon which the severed leaf is wound, a cover for said drum, means yieldingly maintained in said cover to main- 55 tain said severed leaf on said drum, crushing rollers arranged so as to crush the stem
- after the leaf has been severed therefrom, means for advancing the stem from the leaf cutting knives to the crushing rollers, rotary cutting knives for cutting the stem into strips, means associated with said stem stripping knives for crimping the strips, means for picking said strips from said cutting knives and driving means to simultaneously actuate said leaf cutting knives, drum, crushing rollers and stem cutting knives.
17. In a stripping and cutting machine for tobacco leaves the combination of rotary cutting knives adapted to sever the leaf from its stem, a drum upon which the severed leaf 70 is wound, a cover for said drum, means yieldingly maintained in said cover to maintain said severed leaf on said drum, crushing rollers arranged so as to crush the stem after the leaf has been severed therefrom, 75 means for feeding said stem to the crushing rollers from the leaf severing knives, rotary cutting knives for cutting the stem into strips, means associated with said stem stripping knives for crimping the strips, means 80 for picking said strips from said cutting knives, a receiving table for said strips, means to guide said strips to said receiving table, and driving means to simultaneously actuate said leaf cutting knives, drum, crushing rollers and stem cutting knives.
18. In a machine for stripping and cutting tobacco leaves the combination of spaced circular cutting knives adapted to cooperate with spaced circular cutting 85 knives mounted on a drum, said knives adapted to sever the leaf from its stem, crushing rollers to crush the stem, a guide way for said stem to said crushing rollers, means operating in said guide way to advance said stem to said crushing roller, scrapers cooperating with said crushing-rollers, spaced circular knives adapted to cut the stem into strips after it has been crushed, means to guide said crushed stem to said circular knives, means cooperating with said circular knives to crimp the cut strips, means for picking said crimped strips from said knives, and means for transmitting power simultaneously to the leaf severing, stem crushing and cutting means and to said drum.

In testimony whereof I have hereunto set my hand on this 18th day of December, A. D. 1923.

DAVID H. SIMPSON.
